UNITED STATES PATENT OFFICE.

MAX ALFRED LAABS, OF SOUTHBRIIDGE, MASSACHUSETTS, ASSIGNOR TO AMERICAN OPTICAL COMPANY, OF SOUTHBRIIDGE, MASSACHUSETTS. A VOLUNTARY ASSOCIATION OF MASSACHUSETTS.

SPACING MEMBER USED IN FORMING BIFOCAL LENSES.

Application filed May 31, 1921. Serial No. 473,841.

To all whom it may concern:

Be it known that I, MAX A. LAABS, a citizen of the United States, residing at Southbridge, in the county of Worcester and State 5 of Massachusetts, have invented certain new and useful Improvements in Spacing Members Used in Forming Bifocal Lenses, of which the following is a specification.

This invention relates to improvements in 10 the manufacture of lenses and has particular reference to the production of bifocal or multifocal lenses.

One of the leading objects of the present invention is the provision of a novel and improved process for use in uniting the parts 15 of what is commonly termed a fused bifocal lens, and has particular reference to the manner in which the parts are held during the fusing operation so that the air is allowed to gradually escape and at the same 20 time so there will be no interposed wedges, spacing members, or the like in the final or completed blank.

A further object of the present invention 25 is the provision of a novel and improved character of spacing member for use in fused bifocal lens production.

Other objects and advantages of my improved construction should be readily apparent by reference to the following specification taken in connection with the accompanying drawings, and it will be understood that I may make any modifications in the specific details of construction shown and 30 described within the scope of the appended claims without departing from or exceeding the spirit of my invention.

Figure I represents a plan view illustrating the construction of a lens in accordance 40 with my invention.

Figure II represents a sectional view as on the line II—II of Figure I.

Figure III represents a view similar to 45 Figure II showing the completion of the fusing operation.

Figure IV represents a perspective view of my improved spacing member.

Figure V represents an enlarged fragmentary view illustrating the use of a 50 slightly different form of spacing member.

I am aware that prior to my invention bifocal lenses have been produced comprising a main or major blank 1 having formed therein a countersink 2 adapted to receive a

segment 3, the parts being cemented together 55 or united by heating and fusion. Prior to my invention, however, it has been customary to insert a wedge or spacing member under one side of the segment 3 to hold said side raised as the fusing operation starts, 60 it having been necessary for the segment to melt down over and around the spacing member before the operation is completed. This has ordinarily resulted in the embedding 65 of the spacing member in the finished lens, which must be subsequently eliminated either by grinding or cutting off a portion of the lens to get rid of the spacing member, while frequently difficulty has been experienced due to the fact that the portion of the 70 segment immediately adjacent the portion of the wedge would not properly set down into the countersink, leaving an un-united space which renders that part of the blank useless, and is liable to create a certain strain 75 tending to separate the remainder of the blank if kept in stock for any considerable period.

My invention, therefore, consists primarily in the production of a new and novel form of spacing member and an improved process of manufacture embodying said spacing member. This member, as is most clearly shown in the perspective view Figure IV, is generally of L shaped form, comprising the base 4 having rising therefrom the upright portion 5, and being further provided with the shoulder or projection 6, which I make about two-fifths of a millimeter in width, the same being thus very narrow and practically unnoticeable. 80

In use I place the segment 3 over the countersink 2 of the major blank and hold it in position by suitably cementing to the face of the major blank a plurality of L 85 shaped lateral brace members 7 to prevent sliding around or slipping of the segment on the main blank. I then interpose at any suitable position between the blank and segment the shoulder 6 of the member 4—5, the member 5 bearing tightly against the edge 90 of the segment which is held by the member 7 against sliding out of engagement therewith, while the member 6 extends under the segment but only a relatively inappreciable amount. With the segment mounted this 95 small amount is sufficient so that the blank will be initially held by the member 6, the 100

engagement being sufficient to hold the edge of the segment raised until the entire segment is softened and in proper shape for fusion. The edge will be sufficiently soft so that it will slide down over the member 6 for proper uniting with the main blank. In this action there will be but slight distortion of the actual edge of the segment which is substantially unnoticeable, and being the 10 raised portion of the lens will be ground away when the surface of the segment is brought down even with that of the major blank 1 during the grinding operation, while there is no embedment whatever of the parts in the glass, and no difficulty in the removal of the member 4-5.

It will thus be seen that briefly stated my process consists in laterally supporting the segment against sliding movement, and additionally laterally engaging the same to hold it slightly spaced from the major blank 20 at one edge only and in such manner that the heat required for fusion will soften the segment so it will move out of engagement 25 gradually with the spacing member, freeing the spacing member so that it can be re-utilized and the parts united without interfering with the utility of the segment as an entirety and without leaving any perceptible 30 mark on the blank.

Figure V illustrates the spacing member as of slightly different form, being substantially in the shape of a pyramid or a wedge 35 having the slight shoulder as at 9 on which one edge of the lens rests, the pyramid

being firmly seated on the surface of the major blank in the one case and in the other the projection being so slight as to allow the lens to readily move downward past the same without appreciable distortion or without causing the wedge or spacing member to be molded into the blank.

I claim:

1. A spacing member for fused bifocal lenses, comprising a major portion and a segment portion, comprising a body member having an inward projection adapted to underlie the edge of the segment portion and a raised element adapted to abut the edge of the segment portion.

2. A spacing member for use in the formation of fused bifocal lenses having a major portion and a segment portion comprising a body member having a projection at the base, and a raised portion adjoining the projection.

3. A spacing member adapted to be secured on the face of the major portion of a bifocal blank having a base portion to rest on the face of the blank, an upright for engaging the edge of a segment of a bifocal blank and a minute shoulder portion for supporting the segment in raised position.

In testimony whereof I have affixed my signature, in presence of two witnesses.

MAX ALFRED LAABS.
